(57) **CLAIM**

I claim the ornamental design for golfing aid, as shown.

DESCRIPTION

FIG. 1 is the perspective view of the golfing aid.

FIG. 2 is the front elevation of the golfing aid.

FIG. 3 is the left side elevation of the golfing aid.

FIG. 4 is the rear elevation of the golfing aid.

FIG. 5 is the bottom view of the golfing aid; and, FIG. 6 is the top view of the golfing aid.

The broken away section is shown due to indeterminate length.
